UNITED STATES PATENT OFFICE

ALVA L. SKINNER, OF BRIDGEPORT, ILLINOIS, ASSIGNOR TO THE OHIO OIL COMPANY,
OF FINDLAY, OHIO, A CORPORATION OF OHIO

PUMPING POWER

Application filed February 4, 1929. Serial No. 337,514.

This invention relates to pumping power devices and particularly to such devices which are used for pumping a number of oil wells from a single point, or station, at the same time. It is customary for such machines to be in constant operation, day and night, and it is, therefore, necessary for them to be constructed with a view to great durability. It is also necessary for them to be thoroughly lubricated at all times and of simple construction, so as to prevent mishaps necessitating the shutting down of the mechanism with a resultant halt in the pumping. As it is customary to pump a large number of wells with one apparatus it will be readily understood that a stop, for repairs, for a comparatively short time, would result in a material reduction in output.

With the foregoing in view, it is the principal object of this invention to provide a construction possessing durability and simplicity with means for thoroughly lubricating the parts at all times, from a single source and without wastage, and which will prevent foreign matter from entering the working parts.

Another object is to provide a construction which will be compact, readily accessible with respect to its various parts, and that will occupy a minimum amount of space.

Other objects and advantages will be apparent from the following description when taken in connection with the accompanying drawings.

35 In the drawings:

Figure 1 is a vertical sectional view of a pumping power unit made in accordance with the present invention, the same being taken on line 1—1 of Figure 4.

40 Figure 2 is a top plan view of the present invention.

Figure 3 is an enlarged vertical sectional detail view through the overlying portions of the eccentric members.

45 Figure 4 is a side elevation partly broken away.

Figure 5 is an enlarged fragmentary vertical sectional view.

50 Figure 6 is an enlarged horizontal sectional

view illustrating certain horizontal oil ducts in the retaining ring.

Referring particularly to the accompanying drawings, 10 represents a housing in which is mounted a horizontally disposed worm-shaft 11, and a vertical shaft 12. Secured to the lower end of the shaft 12, within the housing 10, is a worm-wheel 13, which meshes with and is driven by the worm-shaft 11. Keyed on the shaft 12, above the housing 10, and arranged in superimposed spaced relation to each other, are the eccentric members 14 and 15, each having a hub portion 16, a channeled rim portion 17, and a series of connecting spokes 18. Upon reference to Figure 1 it will be noted that the major portions of the members 14 and 15 extend in diametrically opposite directions from the shaft 12. The upper face of the bottom wall of the rim portion of the member 14 is formed with the steps 20, 21 and 22, while the outer or marginal wall constitutes an upwardly and outwardly extending flange 17a, having an inwardly directed circum-scribing rib 17b at its upper edge. It will be noted that the marginal wall of the ring 19, adjacent the flange 17a, is inclined to conform therewith and spaced slightly therefrom. This is for a purpose that will be later set forth. Disposed within the channel of the member 14 is a power ring 19, having the shoulders 19' and 23 on its lower face which rest, respectively, on the steps 20 and 22. It will be noted that these shoulders result in an annular groove 24, which overlies the step 21, whereby to provide an oil channel to receive an accumulation of oil to be supplied to the adjacent parts. The periphery of the power ring is formed with an extension bead or rib 25 which extends over the upper face of the flange 17a, to prevent entrance of foreign matter at this point.

To maintain the power ring 19 properly seated within the channel of the rim 17, for rotary movement therein, a retaining ring 26, T-shaped in cross section, has its vertical web 26' disposed between the inner face of the power ring 19 and the inner wall of the channeled rim 17, with its head overlying the power ring 19 and the inner wall of the

channeled rim 17. This retaining ring 26 is secured to the said inner wall by means of screws 27, and between the meeting faces a paper, or other suitable gasket 27a is employed. On the upper face of this inner wall there is formed a vertical bead 28, while a similar bead 29 is formed on the upper face of the power ring 19, and between these beads the said head of the retaining ring 26 is disposed. The beads 28 and 29 are to prevent oil from flowing on the upper surfaces of the adjacent parts on which they are formed.

Formed on the upper face of the power ring 19 are the upwardly extending studs 31, each of said studs having the transverse recess 32, in one side of its upper end, which is intersected by a vertical opening 33 formed through the upper end of the stud, and centrally thereof. A bolt 34 is disposed in the opening 33, with its head seated within said recess. A sleeve 35 is fitted on the stud and has the inner portion of its upper end beveled, as at 36, and rising above the upper end of the stud.

Disposed on the upper end of the bolt, and arranged within the upper end of the sleeve 35, is a beveled disk 38, a nut 39 being engaged on the bolt to properly clamp the parts together, but permitting free rotation of the sleeve on said stud. Extending laterally from the sleeve 34 is a clamp 40, in which is secured one end of one of the pumping rods 41.

Formed in the face of the inner wall of the channel of the rim 17 is a circumscribing oil groove 42, and in the adjacent face of the stem of the retaining ring 26 there is formed a similar groove 42', such grooves being at the same level, and cooperating to form a circumscribing channel. In the inner face of the power ring 19, at the same level as the grooves 42 and 42', is a groove 43, said groove having communication with the groove 42', by means of a series of transverse oil passages 44, formed through the vertical web 26' of the retaining ring 26. Extending from the groove 42, is an oil passage 45 which registers with the lower end of the vertical oil passages 46, formed in the inner portion of the head of the retaining ring 26. Properly secured in the upper end of the passage 46 is one end of an oil pipe or conduit 47. Secured on the upper end of the shaft 12 is a sleeve 48, and formed on the upper end of said sleeve is a cup 49. Connected to the bottom of said cup 49 is the other end of the before-mentioned pipe 47. It will be noted that the pipe 47 leads to a point of the eccentric member 14 near the shaft 12, through the retaining ring 26.

At the upper end of the shaft 12, and properly fitted within the bearing 50, is the cap member 51, for supporting said shaft. This cap is formed with an upwardly ex-

tending peripheral flange 52, through which are disposed, and secured, the inner ends of the radially extending brace rods 53, said rods having their other ends engaged over the uprights 55 anchored therebeyond.

Secured in the bottom wall of the member 51, is a suitable lubricant container 57, preferably of the automatic gravity feed type. Passing through the step 22, of member 14, at a point opposite the passage 45, is a vertical oil passage 58, and secured in the lower end of said oil passage is an oil pipe 59.

The member 15 is of similar construction to that described in connection with the member 14, and has the power ring 60 disposed in its channel, such ring being held in the channel by means of the retaining ring 61, and being provided with upwardly extending studs 31', constructed in a manner similar to the studs 31, of the power ring 19. The power ring 60, and the inner wall of the channel, are formed, respectively, with the oil grooves 63 and 64, between which communication is established by means of the oil passages 60', formed through the vertical web of the retaining ring 61. The groove 64 has the vertical oil passage 65 which registers with the passages 66, in the head of the retaining ring 61. The lower end of the before-mentioned oil pipe 59 is secured within the upper end of this oil passage 66. The lower face of the power ring 60 is formed with the annular oil groove 67, similar to the groove 24, of the ring 19. Leading downwardly through the bottom of the channel of the member 15, from the ledge 68, is an oil passage 69, within which is secured one end of the oil pipe 70, said pipe having its other end secured in the outer end of the oil passage 71, formed in the hub member 16 of the member 15, and which passage extends to a point directly above a bearing 72, which is located in the upper portion of the housing 10, and which surrounds the shaft 12.

The operation of the lubricating system of the mechanism described herein, is as follows: From the lubricant container 57 oil will flow to the bearing 50 and thence to the cup 49. From the cup 49 is passes through the pipe 47, and the head of the retaining ring 26, to the groove 42, through the passages 44, to the groove 43. Here it lubricates the contacting faces of the retaining ring and the power ring 19. The excess then gravitates to the bottom of the channel where it flows over and lubricates the step 20 and the lower face of the shoulder 19', which rests thereon. It then reaches the annular groove 24, where it rises to the level shown in the drawings, and flows over the steps 21 and 22, lubricating the latter, and also the contacting face of the shoulder 23. As the oil is maintained at this level, in the groove 24, it will be seen that the lower portion of the power ring 19 rests in a bath of lubricant. As a result of centrifugal action, a quantity of the oil passes up the inner

slanting wall of the flange 17a, but is prevented from escaping by the flange 17b. Having reached the upper surface of the step 21, the oil then flows through the opening 58, and the pipe 59, to the eccentric member 15, its power ring 60, and its retaining ring 61, which it lubricates in the same manner as described in connection with the eccentric member 14, and its co-acting parts.

10. Passing from the eccentric member 14, through the pipe 70, the oil reaches the housing 10, where it lubricates the bearings 72 and 73, which support the shaft 12, the worm-wheel 13, and the worm-shaft 11, with its bearings 74. Having thoroughly lubricated all of the wearing parts, the oil then accumulates in the housing 10 until it reaches a point determined by the cock 75, in the well known manner. Excess oil and sediment may then be drawn off through the pipe 76, at the bottom of the housing 10.

It will be understood that the herein described mechanism will be operated from any suitable source of power which will be connected to the worm-shaft 11. It will also be understood that any desired number of pumps may be operated from the power rings 19 and 60, within the limit of the studs carried thereby. It will be further understood that numerous changes may be made in the construction of the various parts without departing from the spirit of the invention.

What is claimed is:

1. A pumping power unit including a shaft, a channeled eccentric member mounted on the shaft, the bottom wall of the channel of the member having steps, a power ring seated on the steps within the channel, and means for delivering lubricant between the power ring and said steps.

2. A pumping power unit including a shaft, superimposed channeled eccentric members mounted on the shaft, power rings seated in the channels of said members, retaining rings for the power rings, and means for serially delivering lubricant between said power rings and said retaining rings.

3. A power pumping unit including a shaft, a channeled eccentric member mounted on the shaft, a power ring seated within the channel of said member, a retaining ring for the power ring, and means for supplying lubricant through the retaining ring to the channel of said member.

4. A pumping power unit including an eccentric channeled member the bottom wall of which is provided with steps, a power ring in the channel of the member and having faces resting on certain of the steps, the lower face of the power ring having a lubricant groove arranged over another of the steps, and means for supplying lubricant to the channel of the member and maintaining the same at a predetermined level in said groove.

5. A pumping power unit including superimposed eccentric channeled members, the bottom wall of each of said members having steps, a power ring seated in each channel and having faces resting on certain of the steps, a lubricant supplying means above the members, a conduit for conveying lubricant from the supplying means to one of the steps of one of said members, and a conduit for conveying the lubricant from the other step of said member to one of the steps of the other member.

6. A pumping power unit including a base, a vertical shaft in the base, superimposed eccentric channeled members mounted on the shaft, driving means in the base for the shaft, a lubricant supplying means above the shaft, the bottom wall of each of said members being provided with steps, a power ring in the channel of said member having faces resting on certain of said steps, a groove in the lower face of said power ring disposed over another of said steps to provide a lubricant reservoir, a conduit for conveying lubricant from the supplying means to one of the steps of one of said members, a conduit for conveying lubricant from the other step of said member to one of the steps of the other member, and a conduit for conveying the lubricant from the other step of said member to said driving means.

7. A power pumping unit including a channeled eccentric member, a power ring seated within said channel, and a retaining ring between the eccentric member and said ring and overlying said power ring, the faces of the channeled member and the power ring lying next to the retaining ring having lubricant grooves, and the retaining ring having transverse ducts therethrough establishing intercommunication between the said grooves.

In testimony whereof, I affix my signature.
ALVA L. SKINNER.
